WARMING OVEN

Clarence F. Marquart, Washington, Mo., assignor to
Landshire Products, Inc., St. Louis, Mo.

Filed Mar. 23, 1970, Ser. No. 22,014

Term of patent 14 years

Int. Cl. D7—02

U.S. Cl. D81—10

FIG. 1

FIG. 2

FIG. 3

FIG. 4

FIG. 5

FIG. 6

FIG. 7

FIG. 8

FIG. 1 is a view in perspective of a warming oven embodying my new design;

FIG. 2 is a front elevational view thereof;

FIG. 3 is a side elevational view thereof;

FIG. 4 is a top plan view thereof;

FIG. 5 is a rear elevational view thereof;

FIG. 6 is a bottom plan view thereof;

FIG. 7 is a side elevational view thereof with the upper portion in a raised position; and

FIG. 8 is a view in perspective thereof with the upper portion in a raised position.

The side opposite to the one shown is a mirror image thereof.

I claim:

The ornamental design for a warming oven, substantially as shown and described.
